Warren R. House, ATTORNEY.

UNITED STATES PATENT OFFICE.

JENNIE P. DUVAL, OF KANSAS CITY, MISSOURI.

BED-PAD.

940,958.

Specification of Letters Patent. Patented Nov. 23, 1909.

Application filed July 15, 1908. Serial No. 443,641.

To all whom it may concern:

Be it known that I, JENNIE P. DUVAL, a citizen of the United States, residing at Kansas City, in the county of Jackson and

5 State of Missouri, have invented certain new and useful Improvements in Bed-Pads, of which the following is a specification.

My invention relates to improvements in bed pads.

10 The object of my invention is to provide a bed pad which affords the functions of a bed pan, and which can be used by the patient without inconvenience and without the discomfort connected with the use of a bed pan.

15 The novel features of my invention are hereinafter fully described and claimed.

In the accompanying drawings illustrative of my invention, Figure 1 is a perspective view illustrating the manner of attaching the bed pad to the patient. Fig. 2 is a plan view of the bed pad detached and disposed in a horizontal position. Fig. 3 is a vertical sectional view on the dotted line *a*—*b* of 25 Fig. 2. Fig. 4 is a vertical sectional view on the dotted line *c*—*d* of Fig. 2. Fig. 5 is a longitudinal sectional view of the end of the drainage tube to which is attached the removable closure.

30 Similar characters of reference denote similar parts.

The bed pad comprises in its preferable form, a body portion 1 consisting of a sheet of flexible material impervious to water, such 35 as soft rubber. The body 1 is provided at its edges with a thickened border portion 2, preferably consisting of an inflatable tubular portion, provided with a valved inlet 3 through which the air for inflating may be

40 passed.

The body 1 is provided at one end with a flap 4 which coöperates with the body to embrace the trunk and legs of a person, as shown in Fig. 1.

45 The body 1 with its inflatable border portion 2 forms a receptacle for refuse matter which can pass therefrom by a flexible drainage tube 5 which has one end connected to the bed pad at a point intermediate 50 the portions which embrace the legs of the patient. The other end of the drainage tube

55 is provided with a removable closure 6, preferably a screw threaded plug fitted to an interiorly threaded tube 7 secured to the inner side of the tube 5. Preferably the

outer end of the closure 6 is provided with an eye 8 by which, when not in use, the bed pad may be suspended in an inverted position.

Opposite side edges of the flap 4 have attached to them securing straps 9 having perforations 10 adapted to receive buttons 11 mounted upon similar straps 12 secured to opposite side edges of the body 1. The body portion 1 is also provided adjacent the end opposite that having the flap 4 with securing straps 13 having holes 14 for receiving buttons 15 mounted on straps 16 secured to the body portion 1 at the side edge opposite that to which are secured the straps 13.

In using my invention, the body portion 1 is placed beneath the patient's trunk, as shown in Fig. 1, the straps 13 being secured to the straps 16, as shown. The flap 4 is then passed upwardly between the legs of the patient and is disposed with portions covering the lower part of the patient's trunk and with portions embracing the legs, the flap straps 9 being secured to the straps 12. The tubular border portion is then inflated after the manner of inflating the tube of a bicycle. The drainage tube 5 is then passed beneath the upper covering and over the foot of the bed, the discharge end being vertically disposed. If desired the closure 6 may be removed and the discharge end of the tube 5 disposed so as to discharge into a suitable vessel, not shown. Or the closure 6 may remain in the drainage tube until such time as it may be convenient to remove the pad from the bed. The tube should have sufficient capacity to contain the refuse matter discharged into it, in case it is designed to employ the pad without the use of a separate receiving vessel.

95 By reason of the flexible nature of the bed pad, the patient is not subjected to the discomfort which is unavoidably connected with the use of a bed pan of the ordinary type. In such use the patient must be raised 100 to an unnatural and uncomfortable position, while with the use of my improved bed pad, the patient may lie in a perfectly natural position. The raised border 2 prevents any liquid substance passing from the body portion 1 to the bed covering.

105 Preferably the central portion of the body adjacent the flap 4 is provided with a reinforcing layer 17. This layer, however, 110 may be dispensed with.

My invention may be modified in different ways, within the scope of the appended claims, without departing from its spirit.

Having thus described my invention, what I claim and desire to secure by Letters Patent, is:—

1. A bed pad comprising a body of flexible material impervious to water and having at one end an arcuate notch, a flap joined to the body the full extent of the notch and adapted to extend above and at each side of the notch to embrace the abdomen and legs of a person, the body having portions extending laterally from each side of the notch and which coöperate with the flap to embrace the legs of the person below the apex of the notch.

2. A bed pad comprising a body of flexible material impervious to water and having at one end an arcuate notch, a flap joined to the body the full extent of the notch and adapted to extend above and at each side of the

notch to embrace the abdomen and legs of a person, the body having portions extending laterally from each side of the notch and which coöperate with the flap to embrace the legs of the person below the apex of the notch, the body and flap having an inflatable portion which extends along the upper, side and lower edges of the body and along the lower edges of the portions of the flap which encircle the legs, releasable means for securing together opposing portions of the body and flap where they embrace the legs, and a drainage tube which connects to the body at the apex of the arch.

In testimony whereof I have signed my name to this specification in presence of two subscribing witnesses.

JENNIE P. DUVAL.
